(57) **CLAIM**

The ornamental design for a fitment as shown and described.

DESCRIPTION

FIG. 1 is a top perspective view of a fitment in accordance with our new design;

FIG. 2 is a bottom perspective view of the fitment of FIG. 1;

FIG. 3 is a right bottom perspective view of the fitment of FIG. 1;

FIG. 4 is a front elevation view of the fitment of FIG. 1;

FIG. 5 is a rear elevation view of the fitment of FIG. 1;

FIG. 6 is a left-side elevation view of the fitment of FIG. 1;

FIG. 7 is a right-side elevation view of the fitment of FIG. 1;

FIG. 8 is a top plan view of the fitment of FIGS. 1; and,

FIG. 9 is a bottom plan view of the fitment of FIG. 1.

The evenly dashed broken lines show portions of the fitment and form no part of the claimed design. The dot-dash lines represent the bounds of the claimed design and form no part thereof.

1 Claim, 5 Drawing Sheets
